UNITED STATES PATENT OFFICE.

FREDERICK GELSTHARP, OF TARENTUM, PENNSYLVANIA, ASSIGNOR TO PITTSBURGH PLATE GLASS COMPANY, A CORPORATION OF PENNSYLVANIA.

APPARATUS FOR MAKING PLATE GLASS.

Application filed July 9, 1925. Serial No. 42,536.

To all whom it may concern:

Be it known that I, FREDERICK GELSTHARP, a citizen of the United States, and a resident of Tarentum, in the county of Allegheny and State of Pennsylvania, have made a new and useful invention in Improvements in an Apparatus for Making Plate Glass, of which the following is a specification.

10 The invention relates to apparatus for producing a continuous sheet or ribbon from the body of molten glass. It has for its primary object the provision of improved means for accomplishing the function as above set forth and for producing glass of superior quality which is perfectly flat and relatively smooth, so that it requires a minimum amount of grinding preliminary to polishing in the production of finished plate glass. One embodiment of the invention is 20 illustrated in the accompanying drawings wherein:

Figure 1 is a vertical section through the apparatus on the line I—I of Fig. 2. Fig. 25 2 is a vertical section on the line II—II of Fig. 1. And Fig. 3 is a horizontal section on the line III—III—III—III of Fig. 1.

Referring to the drawings, 1 is the end 30 of a melting tank, preferably of the well known regenerator type having at its end the forehearth or extension 2 with a pair of cut off gates 3 and 4 arranged as indicated in Fig. 1. These gates are supported from above by means of the chains 5 and 6 carried by suitable overhead lifting means, not shown, the gate 3 being of refractory material, such as clay, and the gate 4 being of metal provided with means whereby it may be cooled by a circulation of water. The 35 forehearth 2 is open at the top, and in this space is mounted a pair of sizing rolls 7 and 8, such rolls being journaled at their ends in the standards 9, 9 carried upon the supports 10, 10. The standards are connected to a swing comprising the end members 11, 11 and the transverse rod 12. Provision is made for moving the swing together with the standards and roll carried thereby into and out of position by the use of 40 an overhead crane, not shown, provided with the chains 13, 13 secured to the transverse rod 12. This also provides a means for adjusting the rolls vertically with respect to the

bath, the standards 9, 9 being supported at different elevations upon the members 10, 55 10 by the use of suitable liners.

The ends of the upper roll 8 are carried in suitable journal boxes in the standards 9, 9 and provision is made for adjusting this roll with respect to the roll 7 in the form of 60 wedges 14 operated by screws 15 swiveled to the wedges, this being a common expedient for adjusting rolls, so that no detailed description is necessary. The lower roll 7 preferably has its axle 16 located above the 65 surface of the glass and extending over the side walls of the forehearth, as indicated in Fig. 2, the ends of the roll 7 terminating just inside the side walls of the forehearth, although if desired, the roll ends might extend through the side walls. 70

The rolls 7 and 8 are provided with passages for the circulation of cooling fluid and are connected at their ends with the swivels 17 and 18 by means of which water may be 75 circulated through the rolls. The rolls are driven by means of the tumbler shafts 19, 20, such shafts in turn being driven from the shaft 21 through the intermediary of 80 suitable reduction gearing in the casings 22 and 23.

The glass sheet 24, as it is formed between the sizing rolls 7 and 8 is carried laterally upon a bed made up of the rollers 25, 26, 27, etc. which are hollow and suitably cooled. 85 These rolls are provided at their ends with sprockets and are driven by means of the sprocket chain 28. The temperature of the glass is maintained during its passage from the sizing rolls to the leer 29 by means of the gas burners 30, 31, 32 and 33, which extend laterally across the bed. The cooling of the glass is also retarded by means of the refractory top member 34, such member being removable by means of a crane provided with a chain 35. The rollers 25, 26, 27, etc. constituting the bed are journaled in a suitable frame which is carried upon the truck 36, so that when it becomes necessary, the bed may be moved out of position, thus giving access to the rolls 7 and 8 and to the end of the leer. The leer 29 may be of any approved type, but is preferably of the roller type having the rolls 37, 38, 39, etc. arranged so as to form a continuation of the rolls which constitute the glass receiving bed, such rolls 100 105

being driven by a chain 40 or other suitable driving mechanism. In order to close the triangular spaces at the ends of the rolls, the metal members 41 (Fig. 1) are preferably employed, such members being preferably supported from the arch 42 by means of suitable brackets 43. These members close the spaces at the ends of the rolls and limit the width of the sheet formed.

10 In operation, the rolls 7 and 8 are driven continuously, drawing up from the body of molten glass the sheet 24 which passes over the receiving bed at the right of the rolls and into the leer. The contact of the 15 glass with the rolls 7 and 8, and with the table 11, causes it to set to such an extent that it will not sag to any substantial degree when it passes over the rolls constituting the bed, and from this point on, any 20 unevenness in the glass is flattened out as the sheet progresses over the rollers and through the leer. The glass sheet is annealed in the leer, and cut off at the far end thereof, after which it is ground and 25 polished in the usual way on circular tables or in a straight away surfacing operation. The rolls 7 and 8 size the sheet to substantially its final thickness, the surface formed being relatively smooth as compared with 30 plate glass cast in the usual way on tables, but requiring grinding and polishing due to the marring effect of the surface of the rolls upon the soft glass. When the rolls 7 and 8 and the glass receiving bed are removed, 35 the opening above the forehearth is closed by the cover 44 of refractory material, which is shifted by a crane, whose chain 45 engages the metal swing 46 secured to the cover.

40 What I claim is:

1. In combination, a glass tank having a forehearth or extension having an open top, a pair of horizontally driven and cooled sizing rolls arranged one above the other 45 in said open top with the lower roll partially immersed in the molten glass in the forehearth, and a glass receiving bed extending laterally from a point adjacent the

pass between the rolls for carrying away the glass which is formed. 50

2. In combination, a glass tank having a forehearth or extension having an open top, a pair of horizontal driven and cooled sizing rolls arranged one above the other in said open top with the lower roll partially immersed in the molten glass in the forehearth, standards in which the ends of the rolls are journaled, means for supporting the standards for vertical movement, and a glass receiving bed extending laterally 55 from a point adjacent the pass between the rolls for carrying away the glass which is formed. 60

3. In combination, a glass tank having a forehearth or extension having an open top, 65 a pair of horizontal driven and cooled sizing rolls arranged one above the other in said open top with the lower roll partially immersed in the molten glass in the forehearth, and a glass receiving bed extending 70 laterally from a point adjacent the pass between the rolls for carrying away the glass which is formed, the lower roll being located with its axle above the level of the glass 75 in the forehearth and with its ends lying just inside the inner faces of the side walls of the forehearth. 80

4. In combination, a glass tank having a forehearth or extension having an open top, a pair of horizontal driven and cooled sizing rolls arranged one above the other in said open top with the lower roll partially immersed in the molten glass in the forehearth, standards in which the ends of the rolls are journaled, means for supporting the standards for vertical movement, means for adjusting the upper roll up and down in the standards and a glass receiving bed extending laterally from a point adjacent the pass 85 between the rolls for carrying away the glass which is formed. 90

In testimony whereof, I have hereunto subscribed my name this 29th day of June, 1925.

FREDERICK GELSTHARP.
